UNITED STATES PATENT OFFICE

ALBERT HARRISON DE VOE, OF ELIZABETH, NEW JERSEY, ASSIGNOR TO THE SINGER MANUFACTURING COMPANY, A CORPORATION OF NEW JERSEY.

STRIP-GUIDE FOR ELASTIC FABRICS.

No. 866,006.

Specification of Letters Patent.

Patented Sept. 17, 1907.

Application filed April 4, 1906. Serial No. 309,748.

To all whom it may concern:

Be it known that I, ALBERT HARRISON DE VOE, a citizen of the United States, residing at Elizabeth, in the county of Union and State of New Jersey, have invented certain new and useful Improvements in Strip-Guides for Elastic Fabrics, of which the following is a specification, reference being had therein to the accompanying drawings.

This invention relates to improvements in sewing machine folding devices, and it has for its object to provide means whereby the edges of strips of knit goods may be controlled for proper introduction into such edge-turning devices.

In its preferred form, the present improvement comprises a folding device adapted to turn in the opposite edges of a strip of soft or elastic material, such as knitted fabric, and having adjacent to its mouth or receiving end an uncurling device presenting to the strip of material relatively convex and concave members or implements adapted to successively engage the concave inner face of the curled strip, the former acting as an uncurler and the latter as a slack controller for the edges of the strip previously acted upon by the uncurler. While the strip of knitted goods used in binding the raw edges of certain portions of articles of underwear formed of like material is usually wound upon spools or reels which are mounted upon or adjacent to the sewing machine by which it is applied to the garment, it is in practice impracticable to place such reel sufficiently close to the edge turning guide or binder to prevent the curling of its edges, but by the employment of the present improvement in connection with such guide, the curled edges of the strip are so treated as to insure their proper introduction into the edge-turning device by which the strip is presented to the stitch-forming mechanism in the desired relation to the garment.

In the accompanying drawings, Figure 1 is a side elevation of the forward portion of a sewing machine provided with the present improvement, and Fig. 2 a plan of the same. Fig. 3 is a perspective view, and Fig. 4 a front end view of a binding guide embodying the improvement. Fig. 5 is a sectional elevation of the base-plate of the attachment. Fig. 6 is a perspective view, and Fig. 7 a rear end view of the binding guide in a somewhat simplified form.

The attachment is represented in Figs. 1 and 2 as applied to a Singer double-chain-stitch machine having the bed 1 and overhanging arm 2 carrying the needle-bar 3 with needle 4, the primary presser-foot 5 and feeding presser-foot 6. The bed-plate is offset at the right of the feed-line to form a depression in which is secured by means of fastening screws 7 the attachment base-plate 8 which is provided at its forward end with

a steady-pin 9 having a disk washer 10 intermediate which and the head of such pin is interposed the spring 11, and is provided at its rear end with a pair of upturned lips 12 provided with transverse notches 13 to receive projecting tongues 14 of the flat foot-piece 15 having at its forward end a longitudinal slot 16 embracing said steady-pin beneath the upwardly yielding washer 10 and flared at its forward end to admit the fixed stud 17 upon the base-plate 8.

The tubular binding guide 18 is of the usual U-shape, and is attached to the upturned flange 19 of the foot-piece 15. It is provided along its edges with U-shaped edge-turning channels 20 and terminates at its forward or delivery end in an acute angle where it is provided with guide-hooks 21 to prevent the spreading of the binding strip when reversed for delivery cross-wise of the attachment through the end of the central opening intermediate the binding channels.

As represented in Figs. 1 to 4 inclusive, the arched inner convex body portion of the guide extends rearwardly at 22 slightly beyond the outer concave portion, and merges into a substantially flat backwardly-inclined portion 23 terminating in a cylindrical portion at 24; and the rearward end of the portion 22 is spanned by a bridge-piece 25 conforming therewith in shape and serving as a guard to confine the material upon the flattened portion 23.

The uncurling device comprises a yoke-member 26 having substantially parallel sides pivoted to and embracing the outer extremity of the guide 18 and having an intermediate curved operative portion 27 formed with outer and inner edges 28 which are respectively convex and concave, a transverse guide-bar 29 being secured within taid yoke-member between its curved operative portion and the end of the binding guide.

The yoke-member is represented as pivoted upon its lower side by means of a pin 30 and upon its upper side by means of a thumb-screw 31, whereby it may be clamped in any suitable position of adjustment in relation to the binding guide.

The method of using the device is as follows:—The attachment is first adjusted in position by introducing the forward portion of its foot-piece 15 beneath the yielding washer 10 and pressed forward within the channel intermediate the upturned lips 12 until its lateral tongues 14 are enabled to enter the notches 13, by which the attachment is securely located in operative position with the longitudinal opening intermediate its binding channels substantially at the level of the raised portion of the sewing machine bed-plate, as represented in Fig. 1. The binding tape *a*, which is ordinarily made with raw edges, is then led from the reel, upon which it is commonly wound, from some

suitable position upon or near the sewing machine, first over the convex edge 27, then over the concave edge 28 and under the guide-bar 29 upon the inner member of the binder across the parts 24 and 23 and 5 along the part 22 at the edges of which the corresponding portions of the binding strip enter the edge-turning channels by means of which they are turned to form the selvage upon the binding a' preparatory to stitching it to the fabric b as shown in Figs. 1 and 2. The 10 action of the convex edge 27 is to enter the tubular space embraced by the natural curl of the binding strip, and that of the concave edge 28 is to maintain the central portion of the binding distended, while the outer portions of the latter serve to take up the slack 15 which would otherwise be left by reason of the curvature of the uncurling edge 27. The function of the cross-bar 29 is to maintain the strip taut in its passage from the yoke-member 26 to the mouth of the binder, while the peculiar shape of the adjacent portion of the 20 binder is designed to insure the entrance into the latter of the binding strip fully distended while presenting it in conformity with the shape of the binding channel. As will be observed, the edges of the strip are turned over by the uncurling device in a reverse 25 direction from that which it originally assumed, and such edges are still further turned in the same direction by the edge-turning channels 20 of the binding guide, in order that their elasticity may serve to maintain them in contact throughout with the walls of such 30 channel and in conformity therewith.

The simplified form of the attachment represented in Figs. 6 and 7, is similar in general constructive features to that represented in the preceding figures, but differs therefrom in the omission of the bridge-piece 25 and the flattened backwardly-inclined portion 23 of the inner member of the binding guide; the arched portion 22 merging directly into the cylindrical end of this member. For fabrics of a highly elastic character, it has been found in practice desirable to form 40 the rearward end of the inner member of the guide with the somewhat abrupt curve at the junction of the portions 22 and 23, as represented in Fig. 3, in order that the pull of the strip through the attachment and over such junction may distend the same laterally to insure 45 the proper entrance of its edges into the edge-turning channels of the guide, while the less elastic fabrics have been found to readily enter in proper condition the mouth of the simplified binding-guide represented in Fig. 6, which has the advantage, not only of simplicity of form, but of opposing less resistance to the 50 passage of the strip than the former.

The strip-folding guide shown and described herein is formed with a guiding channel which is slightly arched at its receiving end and merges at its delivery 55 end into U-shape with overlying members 20X, and it will be observed that the uncurling yoke 26 is in all its positions disposed transversely of the delivery end of the folder and in angular arrangement in relation to the general direction of the guide, with the axis of its 60 pivotal pin and clamp-screw also disposed transversely of the overlying members of the channel at the delivery end of the guide. It will be observed that the yoke 26 crosses or intersects the medial plane of the guiding channel intermediate and substantially parallel with 65 the overlying members of the latter at its delivery end,

and therefore maintains a position in advance or in front of the receiving end of the strip-guiding channel, thus avoiding any abrupt bends or sharp angles in the strip in its passage to the guide, so as to insure against any unnecessary distention of the elastic material 70 which would impair the ultimate condition of the work by contraction after the folding and stitching operations, the object of the present improvement being to apply the strip to the margin of the body-fabric with as little distortion as possible, consistent with the 75 proper control of the same in presenting it for the stitching operation.

Although the present improvement is shown in the accompanying drawings as embodied in a sewing machine strip folding device for binding the edges of articles of knit-goods, it is evident that the same is readily adapted for other conditions involving the handling of strips of elastic material, as in winding upon supply reels the strips of such fabric when originally cut from the larger sheets preparatory to its use in connection 85 with a sewing machine, as before described.

While the present improvement is illustrated in the accompanying drawings in two of its approved forms, it will be readily understood that the device is susceptible of considerable modification without departure from the spirit of the invention, the essential feature of which is the provision of the spaced convex and concave edges over which the strip of elastic fabric is successively drawn to open out the same and take up the slack along its opposite edges preparatory 95 to introduction into the tubular guide for giving it the final shape in cross-section in which it is to be delivered to the work or the machine for which it is intended.

By reference to Fig. 1, it will be observed that the delivery end of the binding guide 18 has its lower edge 100 portion disposed slightly below the raised work-plate, in order to present the lower portion of the binding in proper relation to the under side of the fabric b , but that the lateral tongues 14, in conjunction with the notches 13 in the upturned lips 12, act as a transverse pivotal 105 connection with the sewing machine bed for preventing endwise and sidewise displacement of the receiving end of the guide while permitting the upward yield of the delivery end in opposition to the spring 11 so as to enable the attachment to accommodate itself to 110 cross-seams in the fabric to be stitched or to permit the binding to be drawn through the same by hand without excessive resistance when required, preparatory to starting a binding operation.

Having thus set forth the nature of the invention, 115 what I claim herein is,—

1. The combination with a strip-folding guide comprising a channel formed at its delivery end with spaced overlying members, of an uncurling device provided with a plurality of spaced relatively convex and concave operative edges presented successively, in the order named, to the strip and arranged in advance of and in angular relation to the delivery end of said guide and intersecting the medial plane of the guiding channel.

2. The combination with a strip-guide, of an uncurling 125 device provided with a plurality of spaced relatively convex and concave edges having their end portions curved toward the guide into parallel planes at the extreme edges of the latter and presented successively, in the order named, to the material in advance of the mouth of the 130 guide.

3. The combination with a strip-guide terminating at its mouth or receiving end in a cylindrical transverse

member for engagement with the material entering the guide, of an uncurling device provided with a plurality of spaced relatively convex and concave edges presented successively, in the order named, to the material in advance of said transverse member of the guide.

4. The combination with a strip-guide terminating at its mouth or receiving end in a cylindrical transverse member for engagement with the material entering the guide, of an uncurling device provided with a plurality of spaced relatively convex and concave edges presented successively, in the order named, to the material in advance of said transverse member of the guide, and a transverse straight slack-controlling rod interposed between said transverse member and the concave strip-engaging edge, but offset from a direct line between the same and toward the plane of said convex strip-engaging edge.

5. The combination with a sewing machine binding guide having an arched inner member terminating at its receiving end in a transverse cylindrical portion into which the arched portion merges, of an uncurling device provided with a plurality of spaced relatively convex and concave edges presented successively, in the order named, to the material in advance of said transverse cylindrical portion of the guide.

25 6. The combination with a strip-folding guide comprising a channel formed at its delivery end with spaced overlying members, of an uncurling device comprising a yoke-member consisting of a curved bar having relatively convex and concave opposite edges adapted for successive engagement of the material entering the guide, and a pivotal connection intermediate said yoke-member and guide having its axis disposed transversely of the delivery end of said guide, whereby said yoke-member is adapted to be set at different angles in respect of the receiving end 35 of said guide.

7. The combination with a strip-folding guide comprising a channel formed at its delivery end with spaced overlying members, of an uncurling device comprising a yoke-member consisting of a curved bar having relatively convex and concave opposite edges adapted for successive engagement of the material entering the guide, and a pivotal connection intermediate said yoke-member and guide comprising a clamp-screw and having its axis disposed transversely of the delivery end of said guide, whereby 40 45 said yoke-member is adapted to be set and clamped in

different angular adjustments in relation to the receiving end of the guide.

8. A strip-guide comprising a base-plate with means for securing it upon a suitable support and provided upon its upper face with a channel having parallel edges and lateral notches, and a tubular guide member provided with a foot-piece having parallel edges adapted to fit said channel of the base-plate and transverse tongues to enter the lateral notches of said channel, and means for detachably securing said foot-piece yieldingly seated upon the 50 55 base-plate.

9. A strip-guide comprising a base-plate with means for securing it upon a suitable support and having at one end a steady-pin and a washer surrounding the same and a spring for maintaining said washer seated yieldingly upon 60 said plate, and having at its opposite end a pair of parallel guide-lips with transverse notches, and a tubular guide member provided with a foot-piece having at one end a longitudinal slot to embrace said steady-pin beneath its surrounding washer, and at the other end lateral 65 tongues to enter the transverse notches in said guide-lips.

10. The combination with a sewing machine bed comprising a raised work-plate, of a binding guide having one edge of its delivery end normally disposed slightly below the level of said work plate, and a foot by which said guide is sustained having its receiving end connected with the sewing machine frame by a pivotal joint to confine it from endwise and sidewise movement while permitting vertical movement and having at its delivery end means for yieldingly maintaining it in normal position while 70 75 permitting it to yield vertically in respect of said work-plate.

11. The combination with a strip-guide, of an uncurling device provided with a plurality of spaced relatively convex and concave edges presented successively, in the order named, to the strip, and a straight transverse slack-controlling rod interposed between said uncurling device and the mouth of said guide.

In testimony whereof, I have signed my name to this specification, in the presence of two subscribing witnesses. 80 85

ALBERT HARRISON DE VOE.
